MAGNETIC SEWING MACHINE GUIDE

Martin Gross, East Elmhurst, N.Y., assignor to Heimlich Brothers, Inc., New York, N.Y., a corporation of New York

Filed Sept. 23, 1964, Ser. No. 398,706
6 Claims. (Cl. 112—153)

This invention relates to a magnetic sewing machine guide to aid the operator of a sewing machine in sewing a row of stitches at or near the edges of a piece of material.

This application is a continuation-in-part of my application Serial No. 366,120, filed May 8, 1964.

Heretofore, many types of sewing machine guides have been manufactured, some of which have to be screwed or bolted down to the machine, and some of which have to be made integral with the machine.

It is an object of this invention to provide a sewing machine guide which will act as a straight edge or guide to guide the edge of cloth being sewed which may be adjustably moved on the sewing machine with relation to distance from the needle of the machine, and which need not be either bolted to the machine or be an integral part of the machine.

It is a further object of this invention to provide such sewing machine guide which will be held to the sewing machine by means of a magnet.

These objects and advantages are accomplished by the device illustrated in the accompanying drawings in which:

FIG. 1 is a front elevation of the device sitting on the throat plate of a sewing machine, in section and partly cut away, and showing the position of a needle of the sewing machine partly cut away;

FIG. 2 is a top plan view of the device with relation to some cloth being guided thereby, with part of the cloth cut away;

FIG. 3 is a sectional view of the magnet and housing along the lines 3—3 in FIG. 2;

FIG. 4 is a sectional view similar to FIG. 3 of an alternate form of magnet and housing;

FIG. 5 is a top plan view of a throat plate for a sewing machine having guide lines graduated in $\frac{1}{4}$ inch from the needle hole;

FIG. 6 is a sectional view along the lines 6—6 in FIG. 5;

FIG. 7 is a top plan view of the throat plate as shown in FIG. 5 of the device with an alternate form of magnet and housing attached to same;

FIG. 8 is a side elevation of the device as shown in FIG. 7 with a portion cut away for clarity;

FIG. 9 is a medial sectional detail of the alternate form of device shown in FIG. 8; and

FIG. 10 is a sectional view similar to FIG. 9 showing an alternate form of the device in which the plate is magnetized to attract the guide frame.

Similar numerals refer to similar parts throughout the several views.

Referring now to FIG. 1 of the drawings, the device comprises a housing 10 made of metal or plastic. At one edge of the housing 10, there is a straight edge portion 12 which may be made integral with the housing or attached thereto, and within the housing 10 there is contained a magnet 14 shown in phantom in both FIGS. 1 and 2 of the drawings adapted to have strong attraction to the throat plate 16 of the sewing machine. Such a magnet may be of any type. However, I prefer to use an Alnico type magnet strong enough to hold the device to the throat plate of a sewing machine against the normal pressure of an edge or edges 18 of cloth 20.

In operation, the device 10 is placed on the throat plate or other steel part of the machine the desired distance away from the needle 22. The cloth 20 is presented

2

to the machine with edge 18 held against straight edge 12 of the device. The operator moves the cloth 20 forward using the straight edge 12 as a guide and this results in a uniform row of stitches 24 the desired distance from the edge 18 of the cloth 20.

I provide rounded portions 26 and 28 at both ends of the straight edge 12 so that these rounded portions may assist in the guiding function of the device.

It will be appreciated that the device as described may be adjusted at any proper distance from the needle 22, and will be maintained in position as a proper straight edge without the necessity of providing screws, bolts or other fastening means aside from the action of the magnet 14.

In FIG. 4 of the drawings, I show an alternate form of the device which includes inside the housing 10 one or more resilient insert means 32 in addition to the magnet 14. This provision has been made to provide resistance to any possible side slip of the magnetized housing 10. The resilient material 32, such as rubber or any other equivalent material, is adapted to protrude slightly beneath the lower edge 34 of the housing so that it will be somewhat compressed and afford resistance against any surface to which the magnet 14 is attracted by and magnetically secured to.

In FIGS. 5 through 9 of the drawings, I show an alternate form of device in which the housing 10 having a straight edge guide 12 is provided with a lip or tongue 40 adapted to be placed within a groove 42 such as is usual in a throat plate 38 having guide line gradations. In FIG. 5 such a throat plate is illustrated having five grooves 44 suitably adapted to be guides $\frac{1}{4}$ to and including $1\frac{1}{4}$ inches away from center of needle hole 46. Groove 42 mentioned above would be one of the grooves 44 which are usual in such a throat plate 38. The groove, such as groove 42, should have a width of approximately $\frac{1}{32}$ of an inch and a depth of $\frac{3}{128}$ of an inch or greater so as to be adapted to receive a tongue of a width of approximately $3\frac{1}{28}$ of an inch and a depth of approximately $\frac{1}{64}$ of an inch. These measurements are given by way of illustration and are not critical.

It will be appreciated that when the tongue 40 of the device is fitted within a groove 42 and a magnet holds the entire housing down to the machine that it will be extremely difficult, if not impossible, to twist or move the device with relation to the surface of the machine, and that the straight edge 12 will be firm and will maintain its position as a guide.

In order to facilitate removal of the housing 10 for purposes of adjusting same to different guide lines 44, a tail 50 is provided so that the user may flip the entire device up and pivot it on the tongue 40 in the direction of arrow shown in FIG. 8 of the drawings. This breaks the magnetic contact and renders the device easily removable.

In FIG. 10 of the drawings, I show an alternate form of device in which the machine base or throat plate 138 is magnetized and the guide comprises a frame 140 made of steel or other material which may be attracted by the magnetized plate 138. This form of device may also include a tongue 142 as well as grooves 144.

While I have described my device in its preferred forms, there are many forms which it may take without departing from the spirit and scope of the invention. For example, a housing containing a magnet may also contain the resilient material as shown in one alternate form in combination with the tongue adapted to fit in a groove arrangement as shown in the second alternate form, or devices may be constructed with either the resilient material or the tongue and groove arrangement, and there may be other forms of construction as well which come within the claims and spirit of the invention.

In this specification, the magnet guide has been described as being adapted for use with a sewing machine. However, there is no reason why the said guide cannot be used with any type of machine in which a web or sheet of material is fed past any point at which it is desired to have a guide for the edge of the material, and in consequence thereof, wherever the word "machine" appears in the claims hereinbelow, it shall be construed to mean a sewing machine or such other machine as described in this paragraph.

I, therefore desire to be protected for all forms coming within the claims hereinbelow.

Wherefore I claim:

1. A separable and adjustable straight edge guide for a machine, having a main body portion with at least one straight edge portion and comprising magnetic means to releasably fasten the said guide to the said machine and comprising a tongue portion extending from the said main body portion adapted to be selectively received by at least one grooved portion on the said machine.

2. The separable and adjustable straight edge guide for a machine as defined in claim 1 which also comprises resilient means adapted to contact at least a portion of the machine to which the said guide is attached.

3. A separable and adjustable magnetic guide for a sewing machine having a throat plate, of a material adapted to be attracted to a magnet, with grooved guide lines: comprising a housing including a straight edge

portion and tongue means adapted to fit selectively in said grooves of said throat plate, said housing containing magnet means to releasably fasten said guide to said machine.

5. The separable and adjustable magnetic guide as defined in claim 3 which also comprises resilient means adapted to contact at least a portion of the said throat plate when the guide is selectively attached thereto.

10. The separable and adjustable magnetic guide as defined in claim 1, including release means comprising a lateral extension from its said main body portion.

15. The separable and adjustable magnetic guide for a sewing machine as defined in claim 3 comprising release means comprising a lateral extension from its said main body portion.
